FLUID MOTOR

Herbert William Lightfoot and Henry Vincent
Jones, Vancouver, British Columbia, CanadaApplication April 13, 1939, Serial No. 267,674
In Canada October 6, 1938

1 Claim. (Cl. 253—136)

This invention relates to improvements in a fluid motor for a dry shaver. Its primary object being to devise a fluid motor for dry shavers to be operated by water power, and which will not interfere with radio reception. It is of particular advantage where other means of power are not available and also to permit a user to shave in the customary place by a wash basin which in some cases may not have any convenience for other mechanical shavers.

A further object is to provide a fluid motor for a dry shaver to be actuated by water power having means to deliver water under pressure from a wash basin faucet in a confined conduit to increase the velocity of the flow and to provide means for the water to return to the wash basin.

Another object of the invention is to devise a fluid motor for a dry shaver to be actuated by water power from a wash basin faucet under standard pressure from a city or other water supply and to provide a device having fewer working parts than devices for the same purpose now on the market, consequently reducing maintenance expenses and the primary cost of manufacture.

With these and other objects in view that may appear while the description proceeds the invention consists in the novel construction and arrangement of parts as hereinafter more specifically set forth, claimed and shown in the accompanying drawing and in which:

Fig. 1 is a general view showing the manner of attaching the fluid motor to the source of power.

Fig. 2 is a partial section of the fluid motor.

Fig. 3 is a sectional view at right angles to that in Fig. 2.

Fig. 4 is a detail view of the shaver cutter reciprocating means.

Fig. 5 is a sectional view through the cutter head.

Referring more in detail to the drawing in which similar reference characters designate corresponding parts throughout the several views it will be seen the invention consists of a casing 10 having a turbine casing 11 mounted therein, said turbine casing is equipped with a water tight hose connection 12 which forms the waste or discharge line 12 and an inlet conduit 13 of greatly reduced dimensions. A turbine rotor 14 is mounted concentrically in the inner rounded end 15 of the casing fixed on a transverse shaft

16. The conduit 13 is arranged to direct a stream of water at a tangent to the blades 11 of the turbine rotor and the casing is reduced in width adjacent to the turbine to restrict the

passage of water other than through the blades or the turbine rotor.

An eccentric collar 18 is mounted on the shaft 16 in fixed relation thereto and a rocker arm 19 supported on a pivot 20 and having a semi-circular end 21 engages the said collar. Said rocker has an outwardly extending finger 22 which engages the reciprocal element 23 in the cutter head. Said member is equipped with cutting teeth and arranged to work in conjunction with corresponding teeth of the stationary element 24 of the said cutter head. By this means the rotary motion of the turbine is converted to a reciprocal movement for the cutter element.

Spring means are provided to urge the cutter element into engagement with the stationary element. This consists of a flat spring 25 bearing centrally on the shaft support and bent at each end to receive pins 26 which are connected to the cutter element. As the spring is flexible the reciprocal movement of the cutter is not interfered with but is kept moving parallel and in engagement with the stationary element. The pins 26 are positioned in longitudinal slots 27 to allow movement thereof and adjustment means 28 in the form of threadable elements 28 are mounted thereon and arranged to bear against the spring so that a downward movement thereof will increase the spring tension and cause the cutter element to bear stronger against the stationary head.

From the foregoing it will be seen the device as shown constitutes new fluid motor for the operation of a shaver. The water pressure being directed to actuate a turbine rotor by concentration of the flow on the blades thereof and provision being made for the waste or discharge whereby the same is returned to the wash basin waste pipe.

It is believed that the construction and advantages of the structure shown may be apparent from the foregoing paragraphs taken in conjunction with the accompanying drawing without further detailed description.

While the preferred embodiment of the invention has been disclosed it is understood that minor changes in the details of construction, combination and arrangement of co-operating parts may be resorted to within the scope of what is claimed without departing from the spirit of the invention.

We claim:

A fluid motor of the type described comprising a flat rounded casing having an outlet opening from which extends a tubular outlet conduit,

a turbine rotor mounted concentrically in said casing provided with a series of radially extending arcuate blades and a transverse shaft extending at one end beyond said casing, an eccentric collar mounted on the extended end of the rotor shaft, a pivotally mounted rocker arm having a forked end engaged with said collar, an inlet conduit within said outlet conduit, said inlet conduit being relatively smaller than the outlet conduit and extending through the wall of the outlet conduit adjacent said casing with its free end joined to the periphery of the casing

and opening into the casing at a point substantially opposite to the outlet opening of the casing whereby the fluid is discharged from the inlet conduit at a tangent against the blades of said rotor, a flexible hose extending from the said outlet conduit, and a flexible hose extending from said inlet conduit, said last mentioned hose being disposed within said first mentioned hose and connected to a source of fluid under pressure.
